COMBINED RADIO TUNING INDICATOR AND MAGNIFIER

Maurice D. Katz, 35 Broadway, Lawrence, N.Y. 11559

Filed Mar. 12, 1971, Ser. No. 123,940

Term of patent 14 years

Int. Cl. D14—03, 99

U.S. Cl. D26—1

FIG. 1 is a combined tuning indicator and magnifier, showing my new design;

FIG. 2 is a modified embodiment of the tuning indicator illustrated in FIG. 1; and

FIG. 3 is a front perspective of the tuning indicator illustrated in FIG. 1, installed in a radio.

The broken lines representing the radio is shown for illustrative purposes only.

I claim:

The ornamental design for a combined radio tuning indicator and magnifier, substantially as shown and described.
